UNITED STATES PATENT OFFICE.

HORACE PRESCOTT TUCKER, OF NEEDHAM, MASSACHUSETTS.

METHOD OF MAKING INDICATING STRIPS FOR PACKAGES AND AN INDICATING STRIP.

Application filed June 1, 1926. Serial No. 113,007.

The principal object of my invention is to provide a plurality of different marks each giving different specific information as to the contents of packages, such as weight, type, grade, quality or other information and to do so in such a way that one of said plurality as desired will be available for vision in the complete package without waste of time or material in cutting and trimming.

10 It is customary in making packages or labels therefor to so mark the material in sheet or strip form that a plurality of package bodies or labels therefor may be printed, lithographed or otherwise manufactured at one time and each package body or label therefor customarily designates the contents and an indicating mark shows the weight or other information as to the contents, and one object of my invention is to provide such 20 strip or sheet with a plurality of markings to give the same specific information and with another plurality of markings, all of the latter to give the same specific information the latter being different from the first-mentioned specific information, the markings of each plurality being spaced apart a distance equal to a desired dimension of a package body. Another object is to so 30 cut the strip or sheet that each marking of the desired plurality may be available for vision on the completed package or label therefor without waste of material.

In the drawings

Figure 1 is a plan of a large strip showing the lines of one series of cuts;

Figure 2 is a plan of the large strip showing the lines of the other series of cuts;

Figure 3 is an elevation of a complete package embodying one of the smaller strips 40 of Figure 1 but with the cover removed;

Figure 4 is a plan of the package of Figure 3 without the cover;

Figure 5 is an elevation of a complete package embodying one of the smaller strips 45 of Figure 2 but with the cover removed;

Figure 6 is a detail illustrating the spun over base;

Figure 7 is a plan of a different form of 50 large strip, showing the lines of one series of cuts;

Figure 8 is a plan of said different form of large strip showing the lines of the other series of cuts;

Figure 9 is an elevation of a package 55 without the cover and embodying one of the smaller strips of Figure 7;

Figure 10 is an elevation of a package without the cover and embodying one of the smaller strips of Figure 8; and

Figure 11 is a plan, on a larger scale, of 60 the package of Figure 9.

In Figures 1 and 2 I show a large strip or sheet 1 of metal of any desired length having markings arranged in two columns, one for one face of the body of the package 65 and the other for the other face. The strip may be of any desired length and of any desired width, and the number of columns will depend on the width. Each column has a plurality of markings for one class of indication of weight, such as $1\frac{1}{2}$ oz., and a plurality of markings for another class, such as 70 2 oz. Preferably each marking of " $1\frac{1}{2}$ oz." is adjacent to, but spaced somewhat from, a marking of "2 oz." Each column may also 75 include a plurality of markings of the nature of the goods, such as mustard. The markings " $1\frac{1}{2}$ oz." are spaced apart a distance equal to the desired dimension of a package body and the same is true of the 80 markings "2 oz." If it is desired that the large strip be cut so that a small strip in the completed package will show 2 oz. a single line of cutting is made at 2 and 3 and at 4 and at 5, the lines of cutting passing 85 through the words " $1\frac{1}{2}$ oz.", each line of cut forming the adjacent edges of adjacent smaller strips 6, 7 and 8. A small strip, such as 6, is then folded to the form of Figure 4, the ends being soldered, or otherwise connected, together at 9, to form the body of the package, the lower edge, bearing a portion 90 of the words " $1\frac{1}{2}$ oz.", being covered by the spun over base 10. The portion of the words " $1\frac{1}{2}$ oz." at the top of the body are hidden 95 when the cover 11 is applied or would be hidden by a spun over cover, if it were desired to have one. The result is that when the package is complete, that is, with a cover in place, the marking of "2 oz." is 100 available for inspection while no portion of the marking of " $1\frac{1}{2}$ oz." is available.

If it is desired to cut the large strip 1 so as to have the markings " $1\frac{1}{2}$ oz." available for inspection in the complete package the 105 several cuts are made at lines 12, 13, 14 and 15 to form smaller strips such as 16, 17 and 18, the lines of cut passing through the markings "2 oz." A small strip, such as 16, is then folded to form the body of the package, the portion of the words "2 oz." at the 110 bottom being hidden by spun over base 19.

and the other portion of the words "2 oz." at the top being hidden when the cover 20 is in place. In this form the marking "1½ oz." is available for inspection when the 5 package is complete and no portion of the marking "2 oz." is visible.

In Figures 7 and 8 I show a long strip 21 having a plurality of markings of "1½ oz." and a plurality of markings of "2 oz." and 10 in this case similar cuts are made to form smaller strips 22 and 23, or strips 24 and 25, as desired, but these cuts are relatively further apart so that a cut, such as 26 or at 27, forms edges for two small strips, which 15 edges are shorter in length than the edges of the smaller strips such as 28, 29, 30 and 31.

If the cutting is as indicated in Figure 7, the small strip 22, for example, is folded 20 to form the body shown in Figure 9, and the portions of the words "1½ oz." will be hidden in the vertical folded connection of the short edges, as indicated at 32 in Figure 11, while the desired marking of "2 oz." 25 will be available for inspection. If the cutting is as indicated in Figure 8 the small strip 24 will be folded to form the body shown in Figure 10, the marking of "1½ oz." being available for inspection while the 30 portions of the words "2 oz." will be hidden as explained in connection with strip 22.

Although I have particularly described a metal strip I may use a strip of other material such as cardboard or paper and in the 35 latter case, although the paper is really a label, it is a part of the package body in the complete package.

What I claim is:

1. The method of making indicating 40 strips for packages which consists in providing a relatively large strip of material, marking upon the said large strip a plurality of markings of one class of indicants and spaced therefrom a plurality of markings of another class of indicants, spacing the markings of each class of indicants a predetermined distance according to the size 45 of package for which the indicating strip is desired, and cutting the large strip near or through the markings of one of the classes of indicants so spaced into a plurality of smaller strips thereby adapting each smaller strip to serve as a means to indicate the other class of said indicants, the indicants of the class so cut near or through being located by such cutting so as to be invisible when the package is complete.

2. The method of making indicating 60 strips for packages which consists in providing a relatively large strip of material, marking upon the said large strip a plurality of markings of one class of indicants and spaced therefrom a plurality of markings of another class of indicants, spacing the markings of each class of indicants a

predetermined distance according to the size of package for which the indicating strip is desired, and cutting the large strip near or through the markings of one of the classes of indicants so spaced into a plurality of smaller strips thereby adapting each smaller strip to serve as a means to indicate the other class of said indicants, the indicants of the class so cut near or through being located by such cutting so as to be invisible when the package is complete, a single line of cut forming the adjacent edges of two adjacent smaller strips, 70

3. The method of providing indicating strips for packages which consists in providing a relatively large strip of material, marking upon the said large strip a plurality of markings of one class of indicants and spaced therefrom a plurality of markings of another class of indicants, spacing the markings of each class of indicants a predetermined distance according to the size of package for which the indicating strip is desired, each of the markings of one class of indicants being adjacent to but spaced somewhat from one of the markings of the other class of indicants, and cutting the large strip near or through the markings of one of the classes of indicants into a plurality of smaller strips thereby adapting each smaller strip to serve as a means to indicate the other class of indicants, the indicants of the class so cut near or through being located by such cutting so as to be invisible when the package is complete. 80

4. The method of providing indicating strips for packages which consists in providing a relatively large strip of material, marking upon the said large strip a plurality of markings of one class of indicants and spaced therefrom a plurality of markings of another class of indicants, spacing the markings of each class of indicants a predetermined distance according to the size of package for which the indicating strip is desired, each of the markings of one class of indicants being adjacent to but spaced somewhat from one of the markings of the other class of indicants, and cutting the large strip near or through the markings of one of the classes of indicants into a plurality of smaller strips thereby adapting each smaller strip to serve as a means to indicate the other class of indicants, the indicants of the class so cut near or through being located by such cutting so as to be invisible when the package is complete, a single line of cut forming the adjacent edges of two adjacent smaller strips. 90

5. The method of making indicating strips for packages which consists in providing a relatively large strip of material, marking upon the said large strip a plurality of markings of identical indicants and spaced therefrom a plurality of markings of

indicants, identical with each other, but different from those of the first-mentioned plurality, spacing the markings of each plurality a predetermined distance according to 5 the size of package for which the indicating strip is desired, and cutting the large strip near or through the markings of one plurality so spaced into a plurality of smaller strips thereby adapting each smaller strip 10 to serve as a means to indicate the markings of the other plurality, the markings so cut near or through being located by such cut-

ting so as to be invisible when the package is complete.

6. An indicating strip for packages having 15 a plurality of markings of identical indicants and spaced therefrom a plurality of markings, identical with each other, but different from those of the first-mentioned plurality, the markings of each plurality being spaced apart a predetermined distance 20 according to the desired size of package.

HORACE PRESCOTT TUCKER.
